United States Patent Office

Des. 183,640
Patented Sept. 30, 1958

183,640

TROUSERS AND SKIRT HANGER

Laurence W. Van Dusen, Escondido, Calif., assignor to Mission Industries, Escondido, Calif., a corporation of California

Application December 18, 1957, Serial No. 48,940

Term of patent 14 years

(Cl. D80—8)

I claim:

The ornamental design for a trousers and skirt hanger, substantially as shown.
